UNITED STATES PATENT OFFICE.

JOHN ANDREW ADAMS, OF TORONTO, ONTARIO, CANADA, ASSIGNOR TO EDWARD ANDREW ADAMS, OF MONTREAL, CANADA.

CUSHIONED HEEL-PAD FOR BOOTS AND SHOES.

1,211,806.

Specification of Letters Patent.

Patented Jan. 9, 1917.

Application filed August 7, 1916. Serial No. 113,648.

To all whom it may concern:

Be it known that I, JOHN ANDREW ADAMS, of the city of Toronto, in the county of York, in the Province of Ontario, Canada, have invented certain new and useful Improvements in Cushioned Heel-Pads for Boots and Shoes, of which the following is the specification.

My invention relates to improvements in cushioned heel pads for boots and shoes and the object of the invention is to devise a simple form of pneumatic pad which will have a maximum resilience and which will be simple to construct, and at the same time to provide means tending to create an air circulation through the boot to beneath the foot and it consists essentially of the following arrangement and construction of parts as hereinafter more particularly explained by the following specification.

Figure 1, is a sectional view through the heel portion of a boot showing my pad in position and the heel of the wearer placed thereon. Fig. 2, is a perspective detail of my heel pad. Fig. 3, is a longitudinal section through Fig. 2. Fig. 4, is a cross section through Fig. 2. Fig. 5, is a further enlarged perspective detail of one of the resilient tube members employed in the construction of my device.

In the drawings like letters of reference indicate corresponding parts in each figure.

1 indicates the heel portion of a boot, 2 the heel of the boot and 3 the heel of the wearer.

4 indicates my pad. The pad 4 comprises a plurality of tubes 5 arranged parallel one with the other and extending longitudinally of the boot, the inner end of each tube being cut off in a tapered or inclined direction at 6.

7 indicates a perforation formed in the upper peripheral portion of the tube preferably opposite the point where the tapered or inclined portion 6 commences.

8 indicates a wrapping of linen or cotton material which is first laid out flat and coated with cement. The tubes 5 are then laid parallel upon the cemented surface of the cotton and the cotton wrapped around such tubes crosswise of the tubes over the ends of the tubes at 8^x thereby forming a sealed closure for that end of the tube.

X are filling pieces formed preferably of cork.

9 indicates a sheet of asbestos which is laid upon the upper peripheral portions of the tubes 5, that is, on the sides of the tubes in which the perforations 7 are formed.

10 indicates a covering of leather which is preferably formed in two portions 10^x and 10' connected together by a seam 11 extending around the edge of the pad as clearly indicated in the drawings. It will, of course, be understood that the perforation 7 is continued through the cotton wrapping 8, asbestos sheet 9 and outer cover portion 10^x of the cover 10.

The heel pad is placed in the shoe in the position shown in Fig. 1 and when the pressure of the heel bears thereon the tubes 5 are collapsed, the air contained therein being forced out through the perforation 7 and is carried upwardly between the foot of the wearer and the boot to the atmosphere. Upon the pressure of the heel being relieved from the pad the pad returns resiliently to its normal shape, the tubes 5 expanding so as to draw fresh air thereinto through the perforations 7.

From this description it will be seen that I have devised a very simple form of heel pad which will be simple and cheap to manufacture and which will retain its resilience indefinitely, and which, during its operation, will tend to create a circulation of air into the boot beneath the foot of the wearer thereby tending to have a very healthful effect, and which by the employment of the asbestos sheet will prevent the heat of the foot affecting the pad.

Although I have shown my heel pad formed of a series of parallel tubes it will, of course, be understood that the interior of the pad might be made by one continuous resilient chamber equal in area to the horizontal area of the pad and provided with the required number of perforations.

What I claim as my invention is:

1. A heel pad comprising a series of tubular chambers arranged parallel one with the other and having the ends thereof suitably sealed and having perforations in the upper peripheral portions thereof adapted to be located beneath the instep of the wearer.

2. A heel pad comprising a series of tubular chambers arranged parallel one with the other and having the ends thereof suitably sealed and having perforations in the upper peripheral portions thereof adapted to be located beneath the instep of the wearer.

cated beneath the instep of the wearer, and suitable means for binding the parallel tubes together to form the pad.

3. A heel pad comprising a series of tubular chambers arranged parallel one with the other and having the lower peripheral portions of the inner ends thereof tapered off from a point intermediately of their length and having the ends thereof suitably sealed 10 and having perforations in the upper peripheral portions thereof adapted to be located beneath the instep of the wearer.

4. A heel pad comprising a series of parallel tubular chambers having sealed ends and having a perforation in the upper wall 15 of each chamber, and a superimposed asbestos sheet having correspondingly formed perforations, and a suitable cover extending around the same and connecting the parts together.

JOHN ANDREW ADAMS.
